PROCESS FOR TREATING HYDROCARBONS

Ernest A. Bosing, Long Beach, Calif., assignor to
Buffalo Electro Chemical Co., Inc., Buffalo,
N. Y.

Application August 28, 1930, Serial No. 478,445

4 Claims. (Cl. 196—29)

This invention relates to a process for treating hydrocarbons, more especially those hydrocarbons containing sulfur and possessing a bad odor, or which are off color.

6 The method of treating those hydrocarbon distillates, known as "sour" distillates, for improving the odor and color of the same, currently in use, is to add an alkaline solution of lead oxide, doctor solution, to the sour distillate and 10 thereafter add sulfur in its native form for precipitating lead from the distillate as lead sulfide. Numerous disadvantages attend the use of this method, among which may be mentioned the difficulty of adding just sufficient sulfur to 15 entirely eliminate the lead and have no excess of free sulfur remain dissolved in the hydrocarbon. Were the distillate rerun and were it subjected to a subsequent steam distillation, such excess sulfur would be substantially eliminated. This 20 is frequently not done with cracked distillates obtained from California or similar crudes as a sour distillate would be again obtained. Therefore excess sulfur remains dissolved in the distillate and, if the distillate is subsequently used 25 as fuel for an internal combustion engine, such sulfur corrodes metal parts such as the pipe line, carburetor, and motor when starting cold and using the choke.

When elementary sulfur is added to the doctor treated gasoline with the intention of precipitating the lead in the form of lead sulfide, PbS, the distillate is often highly colored due 30 to the formation of lead-sulfur-organic compounds, generally believed to be the cause of 35 this bad color.

The elimination of this color, usually most troublesome in cracked distillates of California crudes, is attempted by filtration through an acid washed clay known as "Death Valley clay", 40 in an attempt to restore its good color. However, when a good color has been restored by such clay treatment, it is not unusual to find a gradual change in the color as the distillate is allowed to stand.

45 One of the objects of my invention is to provide a cyclic method of treating hydrocarbon distillates, regenerating and revivifying certain end products obtained by the treatment whereby said products may be returned to the system and be used for treatment of additional quantities of distillate. I am also able to dispense with the sulfur treatment and yet obtain a distillate free of those constituents which impart 50 a bad color or odor thereto.

55 Further, this method of treatment produces a distillate in which there is no reversion to a colored or sour distillate as would be the case were the sulfur treatment employed, and were 60 the distillate acid treated to the proper extent.

Further, the distillate will possess a permanent good color and odor.

Other objects and advantages will become apparent from the matters hereinafter described in detail and particularly set forth in the claims. 65

The drawing appended hereto shows a flow sheet of the various coordinated steps of the process and method of my invention whereby a sweetened hydrocarbon distillate is produced from a sour distillate, i. e., one possessing a bad 70 odor or color. My process is of great significance in the treatment of certain California petroleum fractions which are produced either by cracking the crude or by a non-cracking distillation although the process may be used to advantage 75 in all sour distillates containing sulfur. In any case, after the acid and alkali wash, these fractions contain certain sulfur compounds which impart to the fractions a bad color and a nauseating odor. It is generally thought that these 80 materials are thio-alcohol or mercaptans, hydrogen sulfide being eliminated by an alkali wash.

It will be readily seen that although I have directed my invention more particularly to a 85 treatment of hydrocarbon fractions obtained from California crudes, the same treatment could be advantageously applied to hydrocarbon fractions obtained from any petroleum oil in which 90 sulfur occurs as an impurity, or could be advantageously applied to any hydrocarbon containing sulfur as thio-alcohol, or in such form as could be readily changed to a thio-alcohol.

Referring more particularly to the flow sheet 95 wherein is outlined a preferred method of working the process, a petroleum fraction obtained by distillation of a given crude is taken from the storage tank or sour distillate storage 10, and caused to enter a reaction chamber 11 by any suitable urging force such as a pump 12. This 100 reaction chamber may be made of a suitable construction and in the conventional form, usually comprises what is known as a turbulence coil, in which a thorough mixing and intimate contact of the distillate and the reaction of material is caused to occur. Prior to the entrance of the distillate to the reaction chamber, chemical reactant is added to the distillate and flows therewith into the reaction chamber. I have found 105 this method of addition advantageous but the chemical reactant may be added at any desirable point in the reaction chamber.

The chemical reactant which is added at this point is a material capable of combining with the mercaptans to form a metallic derivative 115 known as a mercaptide. Certain metals form mercaptides very readily, notably mercury. I prefer to use a metal of the fourth group of the periodic system, such as lead. This solution is the result of a chemical union between lead oxide 120

or litharge and a water solution of caustic soda or sodium hydroxide, giving a chemical compound variously known as sodium plumbite, or Na_2PbO_2 . A solution of the sulfur combining reagent of good strength may be made from forty-two grams of lead oxide, one hundred twenty five grams of sodium hydroxide to the liter.

It is thought that the chemical constituents of this solution, doctor solution, react with the sulfur derivatives, possibly mercaptans, to produce a lead derivative of those substances. A generalized chemical equation of the reaction is given according to the following scheme, where R is a hydrocarbon radical.

The resultant chemical reaction, therefore, produces lead derivatives of the sulfur impurities which remain dissolved in the hydrocarbon and as a by-product, forms an aqueous solution of sodium hydroxide, immiscible with the hydrocarbon. The rate of flow through the reaction chamber, and therefore the time of contact of the distillate with the sulfur combining reagent is so regulated that substantially all of the sulfur derivatives unite to form the sulfur-metal compounds or lead mercaptides. These sulfur-metal compounds are brightly colored, and impart a color to the hydrocarbon which is known as canary yellow.

The method of proportioning the quantities of distillate and sulfur combining reagent is regulated at the entrance point 13 of the reagent. This particular flow-regulating device is of conventional design and may comprise metered and calibrated orifices permitting a regulated flow of predetermined quantities of the fluids to be mixed, which quantities are determinable knowing the amount of sulfur in the hydrocarbon and knowing the strength of the sulfur combining reagent. An efficient mixing of the fluids is obtained by forcing them through a multiplicity of small openings or through a star-shaped diaphragm or other well known device for that purpose.

After the completion of the reaction in the reaction chamber 11, the mixed products are urged into a separator 14 where the treated distillate disengages itself from the water solution of sodium hydroxide so produced and floats upon the surface of the sodium hydroxide. The separated distillate is then removed from the separator container 14 to suitable storage tanks 15 for further treatment, while the solution of sodium hydroxide is drawn off and carried to a suitable mixing tank for the production of reagents, as will be described more in detail hereinafter.

The treated distillate containing in solution certain metal derivatives of the sulfur impurities, for instance lead mercaptide,

is urged into a second reaction chamber 16 which may be of the same general type of construction as the reaction chamber 11 mentioned hereinabove, after removal of excess alkali by means of a water wash if required.

At this point in the procedure, I am able to effectively eliminate substantially all the metallic constituents in the distillate as insoluble oxygen derivatives, which derivatives are subsequently

removed, united with the sodium hydroxide produced in reaction chamber 11 from the treatment with the sulfur combining reagent, thus forming an additional quantity of the reagent which may thereafter be used for treatment of additional quantities of sour distillate. At the same time, the sulfur derivatives are changed to materials which do not impart a bad color or offensive odor to the hydrocarbon or petroleum fraction.

The treatment which I use consists in adding to the distillate containing the colored sulfur-metal derivatives, a solution of an oxygen producing substance, such as a peroxide. Although any peroxide can be used, I have found that hydrogen peroxide is more readily adapted for the purpose than other peroxides, and I add a dilute solution of hydrogen peroxide to the distillate containing the mercaptide whereby the hydrogen peroxide is caused to combine with these mercaptides with the formation of a disulphide, soluble in the distillate, and a metal oxide insoluble in the distillate. The chemical reaction may be shown as follows:

The hydrogen peroxide is added to the stream of hydrocarbon or petroleum fraction either at some point prior to its entrance to the reaction chamber 16, or added directly to the reaction chamber, and the quantities of dilute hydrogen peroxide and the distillate so proportioned that all of the mercaptide must change to disulphide and metallic oxide. The amount of hydrogen peroxide required to effect this desirable change will, of necessity, vary with the composition of the distillate treated. I have found that when treating certain fractions obtained from California crudes which are extremely sour, I have been able to produce a sweet distillate by using one per cent by volume of one hundred volume hydrogen peroxide suitably diluted with water.

I have been able to obtain good results by agitating a given volume of distillate with about one third its volume of extremely dilute aqueous peroxide solution. In one case, one drop of thirty per cent hydrogen peroxide to 33 cc. was used effectively to sweeten 100 cc. of distillate. Slightly elevated temperatures aid my process, as I have greatly facilitated the process at 30° to 40° C.

After the completion of the reaction between the hydrogen peroxide and the lead mercaptides has occurred in the reaction chamber 16, which may be shown by the fact that the hydrocarbon has acquired a good water white color and that additional hydrogen peroxide causes no additional formation of metallic oxide, insoluble in the distillate, the purified and sweet distillate is urged to the separator 17 where the watery sludge of lead oxide 18 is precipitated from the treated and sweetened fraction.

The hydrogen peroxide used for this treatment may be either a hydrogen peroxide of high strength, such as one hundred volume, or thirty per cent hydrogen peroxide, or a more dilute solution, when it is desired to effect a washing action as well as a chemical oxide action in the reaction chamber or turbulence coil 16 and separator 17. For this purpose, the concentrated hydrogen peroxide is obtained from a central storage 19 and diluted to any suitable degree in a dilution tank 150

20, such dilution varying with the treatment desired, although in most cases, being to three per cent hydrogen peroxide or ten volume hydrogen peroxide. This aqueous solution of hydrogen peroxide being of the desired reacting strength is mixed with the distillate carrying the mercaptide at the point 21, which mixture point may be either in the reaction chamber proper or immediately prior to the entrance of the distillate to the reaction chamber.

The separator tank 17 has a suitable bleeder line 21 attached thereto by means of which excess water is removed from the tank and taken to waste, or which may be used thereafter in the process. The lead oxide formed as a sludge by the reaction of hydrogen peroxide upon the lead mercaptides, is drawn from the separator 17 and led to a solution mixing tank 22, while the sweetened distillate is siphoned from the separator 17 and subjected to a subsequent washing, or if sufficiently freed from water soluble impurities, led immediately to a storage tank 23 for subsequent use.

The solution mixing tank 22, made of any suitable design and of materials which will effectively withstand the corrosive action of caustic soda, or other caustic alkali, is provided with an agitator 24 whereby the metallic oxide sludge from the separator 17 and aqueous solutions of caustic alkali from the separator 14 are mixed and caused to unite chemically to form additional solutions of sulfur combining reagent. Theoretically, sufficient quantity of sodium hydroxide is produced in this reaction to completely react with the oxide to form the sodium plumbite. In practice, however, I have found that insufficient amounts of sodium hydroxide are produced due to uncontrollable losses in the process, and therefore, have found it necessary to add a small amount of strong caustic alkali to completely change the oxide sludge to water soluble sodium plumbite and to produce in this solution the requisite alkalinity.

The solution so produced in the mixing tank 22 is thereafter caused to flow by means of the pump 25 to the storage tank 26 where it is ready for use in treatment of additional amounts of sour distillate.

It is thus seen that my process provides an economic cyclic treatment of sour distillates whereby the malodorous compounds, usually mercaptans, are changed to inoffensive disulphides which produce no bad color, or impart no disagreeable odor to the finished distillate. Since the hydrogen peroxide treatment has effectively eliminated all the lead added to the distillate, no color producing lead sulfur compound remains in the distillate, and since it is these compounds which gradually change on standing in air and sun-light to colored derivatives, distillates so treated by my method do not re-acquire an off

color, nor do they gradually assume a bad odor with passage of time, but remain sweet and of good color.

It is therefore unnecessary to treat distillates produced by my method with treated clay in order to insure a water white distillate.

What is claimed is:

1. The cyclic process of treating sour petroleum distillates containing sulfur which comprises treating the distillate with an alkaline aqueous solution of a sulfur combining substance containing lead, separating the treated distillate from the alkaline aqueous residue, treating the recovered distillate with an aqueous solution of hydrogen peroxide sufficient to form an insoluble oxygen compound of lead with the lead compounds in the distillate, separating the insoluble oxygen compound of lead from the sweetened distillate, and thereafter producing an alkaline aqueous solution of the sulfur combining substance by interaction of said insoluble compound and said residue for recirculation in the system.

2. The cyclic process of treating sour petroleum distillates containing sulfur which comprises treating the distillate with an aqueous solution of a plumbite whereby lead derivatives of substantially all the sulfur compounds are produced, separating the treated distillate from the alkaline aqueous residue, treating the recovered distillate with an aqueous solution of a peroxide to form an insoluble oxygen derivative of lead with the lead compounds in the distillate, separating the insoluble oxygen compound of lead from the sweetened distillate, and thereafter producing an alkaline solution of a plumbite by the interaction of said insoluble compound and said residue for recirculation in the system.

3. The process of treating sour petroleum distillates which comprises treating the distillate with an alkaline aqueous solution of a lead compound, separating the treated distillate from the alkaline aqueous residue, treating the recovered distillate at a slightly elevated temperature with a very dilute aqueous solution of hydrogen peroxide sufficient to form an insoluble oxygen compound of the lead contained in the distillate, and thereafter separating the oxygen compound of lead from the sweetened distillate.

4. The process of treating sour petroleum distillates containing sulphur which comprises treating the distillate with an aqueous solution of a plumbite whereby lead derivatives of substantially all the sulphur compounds are produced, separating the treated distillate from the aqueous alkaline residue, treating the recovered distillate with an aqueous solution of a peroxide to form an insoluble oxygen derivative of lead with the lead compounds in the distillate, and separating the insoluble oxygen compound of lead from the treated distillate.

ERNEST A. BOSING. 135
